UNITED STATES PATENT OFFICE.

WALTER C. BROUGHTON, OF KANSAS CITY, MISSOURI.

KNOCKDOWN BUILDING.

Application filed February 18, 1925. Serial No. 10,005.

My invention relates to knockdown buildings and my chief object is to provide a structure in which the component parts may be formed in a central plant and shipped out and set up for use as garages, store buildings, dwellings, and other structures, or be taken down and moved at a minimum expenditure of time and labor.

Other objects will hereinafter appear, and in order that the invention may be fully understood, reference will now be had to the accompanying drawings, in which:

Fig. 1 is a fragmentary side elevation of a portion of one form of the building.

Fig. 2 is a fragmentary vertical cross section on line II—II of Fig. 1.

Fig. 3 is a fragmentary horizontal section on line III—III of Fig. 1.

Fig. 4 is a fragmentary perspective view 20 of a panel and two columns forming part of the wall structure.

Fig. 5 is a fragmentary side elevation of another form of building.

Fig. 6 is a fragmentary vertical section on 25 line VI of Fig. 5.

Fig. 7 is a fragmentary plan view of a portion of the ceiling structure.

Fig. 8 is a broken inverted plan view of one of the ceiling panels.

Fig. 9 is a cross section on line IX—IX 30 of Fig. 6.

Fig. 10 is a cross section on line X—X of Fig. 6.

Referring now to the form disclosed by 35 Figs. 1 to 4, inclusive, A designates a suitable foundation, such, for instance as concrete which is preferably constructed on the site of the building. 2 designates one of the sills which is set upon the foundation A. As dis-

closed more particularly by Figs. 2 and 3, the sills 2 consist of three members—a relatively thin intermediate member 4, an inside member 6, and an outside member 8. The inside and outside sill members 6 and 8, respec-

45 tively, are thicker than the intermediate sill member 4, but the latter projects above the former, as shown by Fig. 2. The three sill members 4, 6 and 8 are nailed, bolted, or otherwise firmly secured together.

50 10 designates a plurality of wall panels consisting, preferably, of concrete. Said wall panels 10 rest upon the intermediate sill members 4 and are supported in upright position by inside and outside columns 12 and 14, respectively, firmly clamped by suitable

means such as bolts 16 to opposite sides of

the panels 10, which are spaced apart at their longitudinal margins as indicated at 18 to admit said bolts 16.

The columns 12 and 14 rest upon the sill members 6 and 8, respectively, and grip and hold top plates 20 upon the panels 10. Stringers 22 are nailed, bolted, or otherwise secured to the outer upper surface of the top plates 20 to reinforce the same and rest upon the upper ends of the outside columns 14. The columns 14 are arranged intermediate corner columns 30, which extend from the sill members 8 to the stringers 22 and are secured to the intermediate sill members 4 and the top plates 20 by suitable means such as bolts 32 and 34, respectively.

36 designates the rafters of the building which rest upon the upper ends of the inside columns 12 and are covered with sheathing 38 upon which a roofing composition 40 is laid.

The building may be provided with suitable doors and windows, but since they do not form a part of the present invention I have not deemed it necessary to show them in the drawings.

In the structure disclosed by Figs. 5 to 10, inclusive, the construction in general, is somewhat similar to the building disclosed by Figs. 1 to 4, inclusive, excepting that air spaces are provided between the walls and the roof to guard against sudden changes in temperature.

Referring now in detail to the different parts, A^a designates the foundation and 50 one of the sills set upon said foundation A^a and which consists of a relatively thin intermediate member 4^a, an inside member 6^a, and an outside member 8^a.

55 10^a designates a plurality of outer wall panels which rest upon the intermediate sill members 4^a and are supported in upright position by inside and outside columns 12^a and 14^a, respectively. The columns 12^a and 14^a are firmly clamped by bolts 16^a to opposite sides of said outer wall panels 10^a, which are spaced apart at their longitudinal margins as indicated at 18^a to admit said bolts 16^a which have one end embedded in 100 the outside columns 14^a, as shown by Figs. 6 and 9.

105 The columns 12^a and 14^a rest upon the sill members 6^a and the foundation A^a respectively, and grip and hold the top plates 20^a upon the panels 10^a. The outer surface of the top plates 20^a are reinforced and covered

by stringers 22^a, which are held in place by the upper portions of the outside columns 14^a.

The outside columns 14^a are arranged in intermediate corner columns 30^a, which extend from the foundation A^a to the upper margins of the stringers 22^a.

The outer sill members 8^a, columns 14^a and 30^a, and stringers 22^a, consist preferably of concrete to correspond with the concrete wall panels 10^a.

Air spaces 42 are formed in the walls of the building by lining the same with inside panels 44, which may be of the same material as the outside panels 10^a. Said inside panels 44 rest upon the foundation A^a and are secured to the inside columns 12^a by suitable means such as upright channel bars 45 and lag screws 46. Said lag screws 46 extend through holes in the channel bars 45 and are screwed into the inside columns 12^a, the panels 44 being spaced slightly apart for the passage of said lag screws 46.

36^a designates the rafters of the building which rest upon the upper ends of the inside columns 12^a and are covered with sheathing 38^a upon which a roofing composition 40^a is laid. An air space is formed at the upper portion of the building by means of the roof and a plurality of ceiling panels 50, which are preferably of the same size and material as the wall panels 10^a and 44. The ceiling panels 50 are supported by a frame consisting preferably of longitudinal channel bars 52 and transverse channel bars 54, which latter are connected to the former by angle plates 56. The longitudinal channel bars 52 are secured by suitable means such as bolts 58 to the inside columns 12^a and are further supported by the upright channel bars 45, which rest upon the foundation A^a. The underside of the

ceiling panels 50 have transverse and longitudinal grooves 64 and 66 to receive upper margins of the channel bars 52 and 54, respectively, and are thereby held from lateral or longitudinal displacement.

From the foregoing description, taken in connection with the drawings, it will be understood that I have provided a building which may be quickly erected or taken down, and while I have shown two forms of the structure, I reserve the right to such other forms as properly fall within the spirit and scope of the invention as claimed.

Having thus described my invention, what I claim and desire to secure by Letters Patent, is:

1. In a building of the character described, a sill consisting of inside, outside and intermediate members the upper margin of which latter extends above the upper margins of the former; vertical wall panels resting upon said intermediate sill member; a top plate resting upon said wall panels; and inside and outside columns resting upon the inside and outside sill members and clamped against the inner and outer surfaces of the intermediate sill member, the wall panels and the top plate to hold them in assembled position.

2. In a building of the character described, a sill, vertical wall panels resting upon said sill, a top plate resting upon said wall panels, a stringer secured to said top plate to reinforce the same, and columns resting upon the sill and clamped against the wall panels and the inner and outer surfaces of the top plate to hold the latter and said panels in assembled position.

In testimony whereof I affix my signature.

WALTER C. BROUGHTON.
